UNITED STATES PATENT OFFICE

2,484,020

AUTOMATIC FEEDING DEVICE FOR CLOTH

Julien Dungler, Basel, Switzerland

Application April 26, 1947, Serial No. 744,263
In France May 24, 1939Section 1, Public Law 690, August 8, 1946
Patent expires May 24, 1959

4 Claims. (Cl. 26—57)

1

This invention relates to automatic devices for introducing or feeding cloth or web in tenter frames or like machines.

It is one of the objects of this invention, to provide an automatic feeding device which is actuated by the selvedge of the cloth and which operates the control of the movement of the corresponding tenter frame inlet according to whether the cloth deviates sidewise from its normal path or whether its width is modified.

It is a further object of the invention to provide efficient control means for the track or rail of each tenter frame inlet, while for starting the operation of the frame an electric contact-maker is placed at the selvedge, said contact-maker further controlling said inlet rail through a speed reducing mechanism and a screw-and-nut transmission.

It has been recognized that although the electric feeding devices hitherto proposed provide desirable regularity and accuracy of guiding, as long as the feed is effected at low speed, their operation becomes irregular and they lose their accuracy as soon as the feeding operation is performed at high or even medium speeds; such devices thus become inefficient and useless, in particular when applied to pin tenters wherein it is of utmost importance to maintain a regular and accurate guiding.

This defect is due to the fact that, owing to their inertia, the various rotary elements of the drive of each tenter frame inlet do not stop instantly when the contact-breaker actuated by the selvedge cuts off the current which is supplied to the electric motor; the movement of the tenter frame inlet therefore only stops after a certain delay.

Endeavors have been made to overcome this inertia effect by means of a braking action which becomes effective at the exact instant when the circuit of the motor is broken; now, such braking action can only reduce the inertia of the mechanism to a certain extent, but is incapable of eliminating it completely.

Therefore, a further purpose of the invention is to provide automatic feeds or feeding devices which are capable of operating correctly, even at highest feeding speeds (which may, at the present time, in some drying tenters exceed 100 meters per minute), and to this end, the invention has for one of its important objects the provision of coupling means interposed between the screw or other member effecting the movement of the tenter inlet and the rotary elements which receive their movement from the motor, which

2

coupling means effect at the required moment the instant separation of the screw from the other elements of the transmission.

One embodiment of the invention is described hereinafter and illustrated diagrammatically, merely by way of example, in the accompanying drawing, in which:

Fig. 1 is a side-elevational view of an improved electric feeding device; and

Fig. 2 is a detail view, on a larger scale, showing the coupling of the feeding device according to the invention.

Fig. 3 is a wiring diagram employed in the electric device of Fig. 1.

It is, of course, understood that the drawing only indicates one part of the device since corresponding or similar parts thereof are provided at each selvedge.

Referring now to the drawing, there is designated by numeral 1 the movable inlet rail of a tenter frame in which each selvedge 2 of cloth 15a is controlled by an electric feeler 3 of any known type.

According to Figs. 1 and 3 this feeler 3 has, for instance, a fork 16 in which is moved the selvedge 2 of the fabric 15a to be controlled. The fork 16 is secured to a contact lever 17 pivoted at 18 and under action of a spring 19. The contact lever cooperates with two fixed contacts 20 and 21 for energizing the relays 22 or 23 from the three phase network 24. Each relay has two sets of contacts 25, 26 and 27, 28, respectively, the purpose of which will be explained hereafter.

On screw-threaded rod or spindle 4, there is mounted a nut 29, which is secured to the tenter inlet rail, the rotary movement of spindle 4 producing a rectilinear movement of such nut, by which said rail may be moved outwardly or inwardly following the direction of rotation of spindle 4.

An electric motor 5 actuates by means of a belt 6 a pulley 7 which is loosely mounted on the screw-threaded spindle 4.

On pulley 7 and between its spokes are arranged electro-magnets 8 cooperating with coupling means consisting of a soft iron ring 9 so as to attract it when they become energized; a soft iron ring 9 secured to ring 10 (made of non-magnetic material), which in turn is connected in any appropriate manner to radial flexible blades 11, the latter being retained on sleeve 12 at flange 30 thereof. Sleeve 12 is attached to spindle 4 by means of key 31.

When the electro-magnets 8 are deenergized, the springiness of the blades 11 retracts the ring

10 so that there is no contact between the iron ring 9 and the electro-magnets 8.

If, on the contrary, the electro-magnets 8 will become energized, the iron ring or element 9 is attracted so that it lies against the electro-magnets 8 owing to the flexibility of the blades 11. Element 9 is thus held by the electro-magnets 8, whereby the pulley 7 is secured to the spindle 4.

On the hub of pulley 7, there is provided an 10 insulating ring 13 supporting, as known per se, two rings 14 connected by wires 34 to the contact sets 26 and 28 of the relays 22 and 23, respectively. The rings 14 are further connected by wires 35 to the electro-magnets 8 arranged in 15 series or in parallel on pulley 7.

Furthermore, a mechanical brake may be provided, equipped with a lever 15 which supports a brake shoe 36 at one end and is pivoted at 37 at the other end. The lever 15 is urged by a 20 spring 38 so as to apply the brake shoe 36 constantly against the pulley 7. This brake does not interfere with the normal working of the device but reduces the duration of the rotation of pulley 7 and motor 5 after the interruption of the electric circuit of the latter.

The electro-magnets 8 are fed from a direct current source 39 which is connected to contact sets 26 and 28 of relays 22 and 23, respectively.

The device works as follows: As long as the selvedge 2 of the fabric 15a is correctly presented at the inlet of the tenter frame, the fork 16 is maintained in its neutral position and so is contact finger 17 of the feeler 3. In this position, none of the relays 22 and 23 is energized, so that no current will be supplied either to motor 5 or to electro-magnets 8. Consequently, the mechanism remains inoperative.

When now the fabric deviates outwards or becomes larger, its selvedge 2 abuts against fork 16 and urges the same to the left (Fig. 3) so as to apply finger 16 against contact 20, thus energizing relay 22 which closes its contacts 25 and 26. The closing of contact set 25 causes a rotative movement of motor 5 and thus rotates pulley 7 in a direction as to move inlet rail outwardly. At the same time, the closing of the contact set 26 has energized electro-magnets 8 from the supply source 39 by means of wires 34, rings 14 and wires 35. Consequently, the soft iron ring 9 is 50 attracted and lies against electro-magnets 8, so that the sleeve 12 keyed to the spindle 4 is now driven by pulley 7. Due to the rotation of spindle 4, the nut 29 is advanced in such a way that the inlet rail 1 mounted thereupon is moved outwardly.

When, due to this outward movement of the rail 1, the pressure exerted by the selvedge 2 on fork 16 diminishes, spring 19 retracts finger 17 towards its neutral position thus deenergizing the relays 22. Consequently, the current supply is cut off from motor 5 and electro-magnets 8. This produces stoppage of motor 5 and pulley 7, the duration of the rotation by inertia being reduced by the brake mechanism 15, 36, 37, 38. At the same time, deenergizing of the electro-magnets 8 uncouples pulley 7 from sleeve 12 as the springy blades 11 retract the soft iron ring 9 from the electro-magnets 8. Thus, the stoppage of spindle 4 and of the inlet rail is nearly instantaneous since their inertia is rather small and much smaller than that of the motor and the pulley.

If, on the contrary, the fabric deviates inwards or becomes narrower, the pressure of the selvedge

5 on the fork 16 ceases thus permitting spring 19 to apply finger 17 against contact 21. This produces energization of relays 23 which closes its contact sets 27 and 28. The closing of contacts 27 causes rotation of motor 5 in a direction opposed to that when fed by the contacts 25. As at the same time electro-magnets 8 are energized by contacts 28, pulley 7 is coupled to sleeve 12 and thus to spindle 4, the inlet rail 1 being thus moved inwardly. When due to this movement the contact is restored between the selvedge 2 and the fork 16, the finger 17 is brought back to its neutral position, thus cutting off the current from relays 23.

This produces the nearly instantaneous stoppage of the inlet rail, as shown before.

It is well understood that a separate device of the kind shown is provided for both of the selvedges of the fabric.

Of course, the invention is in no way limited to a particular embodiment and it is possible to imagine modifications and improvements of details without exceeding the scope of the invention.

It can thus be seen that there has been provided in accordance with this invention a feeding mechanism for supplying cloth to tenter frames and like machines having adjacent their inlets electric contact means for cooperation with the selvedge of said cloth and for regulating supply of current to a motor; controlling means for adjusting the distance between the tenter inlets, said controlling means including a threaded spindle, a member disposed for movement on said spindle and operatively connected with said tenter frame, a pulley in driving connection with said motor and loosely mounted on said spindle, electro-magnetic means carried by said pulley, coupling means including a soft iron ring adapted for cooperation with said electro-magnetic means, 40 said coupling means being fixedly connected with said spindle, whereby said pulley may be clutched through said coupling means with said spindle for effectuating adjustment of said tenter inlets, and brake means responsive to interruption of current supply to said motor and for stopping rotation of said pulley.

Having thus described the invention, what is claimed as new and desired to be secured by Letters Patent, is:

1. In a feeding mechanism for supplying cloth to tenter frames and like machines having a motor and adjacent their movable inlets electric contact means for cooperation with the selvedge of said cloth and for regulating supply of current to said motor; controlling means for correspondingly adjusting a tenter inlet in response to lateral deviations of said cloth as it is fed to the inlet, said controlling means including a threaded spindle, a member disposed for movement on said spindle and operatively connected with said tenter frame, a pulley in driving connection with said motor and loosely mounted on said spindle, electro-magnetic means carried by said pulley, and coupling means including a soft iron element 60 adapted for cooperation with said electro-magnetic means, said element being carried by said spindle, whereby said pulley may be clutched through said coupling means with said spindle for effectuating adjustment of said tenter inlets.

2. In a feeding mechanism for supplying cloth to tenter frames and like machines provided with a motor and adjacent their movable inlets with electric contact means for cooperation with the selvedge of said cloth and for regulating supply of current to said motor; controlling means for

correspondingly adjusting a tenter inlet in response to lateral deviations of said cloth as it is fed to the inlet, a movable member operatively connected with said tenter frame, an element arranged for driving connection with said motor, electro-magnetic means carried by said element, and coupling means adapted for cooperation with said electro-magnetic means and operatively connected with said member for displacing the same to effectuate adjustment of the position of said tenter inlets.

3. In a feeding mechanism for supplying cloth to tenter frames and like machines having a motor and adjacent their movable inlets electric contact means for cooperation with the selvedge of said cloth and for regulating supply of current to said motor; controlling means for correspondingly adjusting a tenter inlet in response to lateral deviations of said cloth as it is fed to the inlet, said controlling means including a threaded spindle, a member disposed for movement on said spindle and operatively connected with said tenter frame, a pulley in driving connection with said motor and loosely mounted on said spindle, electro-magnetic means carried by said pulley, coupling means including a soft iron ring adapted for cooperation with said electro-magnetic means, and means on the hub of said pulley for distributing supply of electric current to said electro-magnetic means, said coupling means being fixedly connected with said spindle, whereby said pulley may be clutched through said coupling means with said spindle for effectuating adjustment of said tenter inlets.

4. In a feeding mechanism for supplying cloth to tenter frames and like machines having a motor and adjacent their movable electric contact means for cooperation with the selvedge of said cloth and for regulating supply of current

to said motor; controlling means for correspondingly adjusting a tenter inlet in response to lateral deviations of said cloth as it is fed to the inlet, said controlling means including a threaded spindle, a member disposed for movement on said spindle and operatively connected with said tenter frame, a pulley in driving connection with said motor and loosely mounted on said spindle, electro-magnetic means carried by said pulley, coupling means including a soft iron ring adapted for cooperation with said electro-magnetic means, said coupling means being fixedly connected with said spindle, whereby said pulley may be clutched through said coupling means with said spindle for effectuating adjustment of said tenter inlets, and brake means responsive to interruption of current supply to said motor and for stopping rotation of said pulley.
